US00D629051S

(12) **United States Design Patent**
Nishimoto

(10) **Patent No.:** US D629,051 S
(45) **Date of Patent:** ** *Dec. 14, 2010

(54) **TOY TOP**(75) Inventor: **Hisao Nishimoto**, Tokyo (JP)(73) Assignee: **Tomy Company, Ltd.**, Tokyo (JP)(**) Term: **14 Years**(21) Appl. No.: **29/311,821**(22) Filed: **Jul. 2, 2009**(30) **Foreign Application Priority Data**

Jan. 9, 2009 (JP) 2009-000395

(51) **LOC (9) Cl.** ..... 21-01(52) **U.S. Cl.** ..... **D21/460**(58) **Field of Classification Search** D21/385, D21/386, 390, 398, 404, 436-438, 441-444, D21/451, 453, 455, 458, 460-464, 563, 578, D21/585, 592; 446/34, 36-48, 217, 218, 446/236-266, 330, 352, 358, 359, 366, 368, 446/429, 430

(57) **CLAIM**

The ornamental design for a toy top, as shown and described.

DESCRIPTION

FIG. 1 is a perspective view of the toy top showing my design;

FIG. 2 is a front view thereof;

FIG. 3 is a rear view thereof;

FIG. 4 is a top view thereof;

FIG. 5 is a bottom thereof;

FIG. 6 is a right side view thereof; and,

FIG. 7 is a left side view thereof.

The broken lines are included for the purpose of illustrating portions of the toy top that form no part of the claimed design.
